DESIGN FOR A HINGE

Earl M. Borchers and Charles C. Unzicker, Rockford, Ill., assignors to American Cabinet Hardware Corporation, Rockford, Ill., a corporation of Illinois

Application August 2, 1944, Serial No. 114,698

Term of patent 7 years

(Cl. D10—7)

To all whom it may concern:

Be it known that we, Earl M. Borchers and Charles C. Unzicker, citizens of the United States, residing at Rockford, in the county of Winnebago and State of Illinois, have invented a new, original, and ornamental Design for a Hinge, of which the following is a specification, reference being had to the accompanying drawing, forming a part thereof.

Fig. 2 is a side edge view of the hinge shown in Fig. 1.

Fig. 3 is a sectional view taken on the line 3—3 of Fig. 1.

We claim:

The ornamental design for a hinge, substantially as shown.

EARL M. BORCHERS.
CHARLES C. UNZICKER.
